INVENTOR:
John W. Cosgrove.

UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

CEMENTING-MACHINE.

1,318,480.

Specification of Letters Patent.

Patented Oct. 14, 1919.

Application filed May 1, 1918. Serial No. 231,917.

To all whom it may concern:

Be it known that I, JOHN W. COSGROVE, a citizen of the United States, residing at Medford, in the county of Middlesex and State 5 of Massachusetts, have invented certain Improvements in Cementing-Machines, of which the following description, in connection with the accompanying drawings, is a specification, like reference characters on the 10 drawings indicating like parts in the several figures.

This invention relates to machines for applying cement to various objects. It is especially applicable to machines for cementing fabrics and the like arranged in one or 15 more layers of varying thickness.

In the manufacture of various goods, such as waterproof garments including raincoats and ponchos, a portion may be produced in 20 which one layer of fabric at seams or hems extends over another irregularly, so that along the area which is to be cemented the work may be at some points two layers in thickness and at other points but one. A 25 machine for uniformly applying the cement to work of this character is furnished by the present invention.

A feature of the invention consists in a work-support arranged in sections situated 30 opposite the cement-applying member, one of the sections being yieldable and normally lying at a different distance from the applying member than another section, it usually being nearer to said applying member. 35 Preferably, the yieldable section of the work-support is relatively narrow as compared with the adjacent section, and is here shown in the form of a spring-finger, while the wider section may be a roll, to the periphery 40 of which a portion of the finger is concentric.

In connection with the following description and claims, other features will appear.

In the accompanying drawing, 45 Figure 1 is a perspective view of one embodiment of my improved machine, viewed from below;

Fig. 2 is a similar view of the work-supporting lever with its elements separated;

Fig. 3 is a partial vertical section of the work-support somewhat enlarged; and

Fig. 4 shows in perspective a portion of the work which may be operated upon.

A frame 10, upon which is supported a

cement-tank 12 and having journaled in it 55 a shaft 14 for the cement-applying member, may be substantially as disclosed in my Patent No. 1,242,925, dated October 16, 1917. The applying member 16 for receiving cement from the tank and transferring it to 60 the work is shown as a solid roll having transverse cement-pockets 18 joined by distributing grooves 20 formed circumferentially of the applying face of the roll. Fully crumpled in the frame, as in the previously 65 mentioned patent, is a carrier-lever 22 having at its outer end an upwardly extending portion 24. Journaled in this extension is a horizontal spindle 26 having fixed upon its inner extremity a roll 28, which furnishes 70 one section of a work-support. The outer edge of the roll 28 is preferably in vertical alinement with the opposite edge of the applying roll, and the supporting face extends for a considerable portion of the width of 75 the applying roll adjacent to its opposite edge. Beyond the roll 28, between it and the inner edge of the applying roll, is a yieldable section of the work-support. This is shown as a spring-finger 30 of some such 80 flexible material as steel, having the same curvature as the periphery of the roll 28. It extends from the rear of the machine over the lever 22 concentric to the roll, and then vertically downward to a shank or enlargement 32, by which it is mounted in the lever. The shank lies in a recess or vertical way 34, being held therein by a screw 36 threaded into the lever with its head overhanging the 85 recess, so that it contacts with a projecting portion of the shank. The finger 30 lies outside the periphery of the roll 28, so that it tends to force the work resting upon it above the roll, yet may yield to such a horizontal position as to furnish a continuation of its 90 supporting surface. The normal relation may be changed by raising or lowering the shank in the way 34.

At the outer edge of the supporting roll 28 beyond the edge of the applying roll 16 100 is another work-supporting section, which maintains the portion of the material adjacent to that operated upon horizontal, so that it may be presented properly to the applying roll. This I have illustrated as consisting of a curved table 38, the outer surface being preferably in horizontal alinement 105 with the periphery of the roll 28. The table

is carried by a shank 40 recessed at 42 to receive a projection 44 at the end of the lever 22, thus furnishing a way permitting vertical adjustment of the table. The table 5 is held in position by a screw 46 passing through a slot in the shank 40.

A gage 48, adjustably held upon the lever 22 by a screw 50, determines by its contact with the edge of the work the points of application 10 of cement thereto. The contact face of this gage is closely adjacent to the inner edges of the roll 16 and finger 30.

In Fig. 4 is illustrated a fragment of an edge or hem portion of a garment which 15 has been cemented by this machine. It consists of inner and outer layers I and O, respectively, of fabric, secured by a line L of stitching. At o the inner layer projects over the outer irregularly, so that portions come 20 fully to the edge of the layer O, while other portions extend only to i at a little distance from the edge of the layer O. In applying the cement indicated at C to both a strip along the edge of the layer I and to the portions 25 of the layer O over which the projections o do not extend, the finger 30 is preferably so adjusted that normally, or when out of contact with the work, its upper surface lies outside the periphery of the roll 28 30 a distance substantially equal to, or at least not less than, the thickness of the inner layer of fabric. As a result of this, when the work is introduced between the applying roll and the work support and is advanced 35 for the application of cement by the former, the finger 30, which is of approximately the same width as the projection portions o when in contact with these projections, yields so that it lies at the same level as the 40 periphery of the supporting roll. When a space between the projections o is reached, the finger moves upwardly until the inner surface of the layer O is raised to the same level as the layer I, so that the cement is distributed 45 uniformly by the roll 16 over the entire surface. For any variations in the thickness of the material the finger readily yields, while always holding the edges of both layers of fabric against the applying 50 roll.

Having fully described my invention, what I claim as new and desire to secure by Letters Patent of the United States is:

1. In a cementing machine, a cement-applying member, and a work-support including a plurality of sections situated opposite the applying member, one of said sections being yieldable and normally lying at a different distance from the applying member 55 than another section.

2. In a cementing machine, a cement-applying member, and a work-support including a plurality of sections situated opposite the applying member, one of said sections 60 being yieldable and normally extending

nearer the applying member than another section.

3. In a cementing machine, a cement-applying member, and a work-support including a plurality of sections situated opposite the applying member, one of said sections being of flexible material and normally extending nearer the applying member than an adjacent section. 70

4. In a cementing machine, a cement-applying member, and a work-support including a plurality of sections situated opposite the applying member, one of said sections extending for a considerable portion of the width of the applying member and another section 80 adjacent to the wider section being relatively narrow and yieldable. 75

5. In a cementing machine, a cement-applying member, and a work-support including a plurality of sections situated opposite the applying member, one of said sections being yieldable and normally extending nearer the applying member than another section, said yieldable section being so constructed and arranged that the amount of its 85 projection beyond the other section may be varied. 90

6. In a cementing machine, a cement-applying member, and a work-support including a rotatable roll and a spring-finger situated adjacent to the roll. 95

7. In a cementing machine, a cement-applying member, and a work-support including a rotatable roll extending from a line in proximity to one edge of the applying roll 100 to a line adjacent to the opposite edge of the applying roll, and a spring finger situated between the edge of said roll and the edge of the applying member.

8. In a cementing machine, a cement-applying member, a work-support including a rotatable roll, and a spring-finger situated adjacent to the roll, and means for adjustably mounting the spring finger. 105

9. In a cementing machine, a cement-applying roll, a carrier member extending opposite the applying roll, a work-supporting member rotatable in the carrier member, and a work-supporting member fixed against movement on the carrier member at each side 110 of the rotatable member.

10. In a cementing machine, a cement-applying roll, a carrier member extending opposite the applying roll, a work-supporting member rotatable in the carrier member, and a work-supporting member fixed to the carrier member at each side of the rotatable member, one of said supporting members extending nearer to the applying member 115 than do the others. 120

11. In a cementing machine, a cement-applying roll, a carrier member extending opposite the applying roll, a work-supporting member rotatable in the carrier member, and a work-supporting member fixed to the car- 125 130

rier member at each side of the rotatable member, one of the first supporting members extending beyond the rotatable member toward the applying member.

5 12. In a cementing machine, a cement-applying roll, a carrier member extending opposite the applying roll, a work-supporting member rotatable in the carrier member, and a work-supporting member fixed to the carrier member at each side of the rotatable member, one of said fixed members being flexible.

10 13. In a cementing machine, a cement-applying roll, a carrier member extending opposite the applying roll, a work-supporting member rotatable in the carrier member, a work-supporting member fixed to the carrier member at each side of the rotatable member, one of said supporting members extending nearer to the applying member than do the others, and mountings for the fixed members in which they may be secured in different relations to the applying member.

15 14. The combination with a frame, of a cement-applying roll rotatable therein, a lever fulcrumed in the frame below the applying member and having transverse ways and an upward extension, a work-supporting 30

plying member and having transverse ways and an upward extension, a work-supporting roll journaled in the extension, and a work-supporting member mounted in the ways. 30

15 15. The combination with a frame, of a cement-applying roll rotatable therein, a lever fulcrumed in the frame below the applying member and having transverse ways and an upward extension, a work-supporting 35

roll journaled in the extension, and a work-supporting finger provided with a shank mounted in the ways and a flexible portion

extending concentric to the periphery of the roll. 40

16. The combination with a frame, of a cement-applying roll rotatable therein, a lever fulcrumed in the frame below the applying member and having a plurality of transverse ways and an upward extension, a 45

work-supporting roll journaled in the extension, and work-supporting members mounted for adjustment in the ways at each side of the rotatable member.

In testimony whereof I have signed my 50 name to this specification.

JOHN W. COSGROVE.
